BURNER BLOCK

Emil Blaha, Cheltenham, Pa., assignor to Selas Corporation of America, Philadelphia, Pa., a corporation of Pennsylvania

Application June 23, 1945, Serial No. 601,305

11 Claims. (Cl. 158—1)

1
My invention relates to refractory shapes, such as, for example, burner blocks, filler blocks, roof shapes and the like, and it is an object to provide an improvement for increasing the life of such refractory shapes employed in walls of heating structures.

The objects and advantages of my invention will become apparent from the following description and accompanying drawing forming a part of this specification, and of which Fig. 1 diagrammatically illustrates a fragmentary perspective view of a refractory wall for a heating structure in which are mounted refractory shapes embodying the invention; Fig. 2 is a vertical sectional view, taken at line 2—2 of Fig. 1, of a burner block embodied in the refractory wall; Fig. 3 is a vertical sectional view taken at line 3—3 of Fig. 4; Fig. 4 is a horizontal sectional view taken at line 4—4 of Fig. 3; Fig. 5 is a perspective view of one form of tie rod employed in the refractory shapes mounted in the wall of Fig. 1; and Fig. 6 is a sectional view of another form of tie rod employed in the refractory shapes mounted in the refractory wall of Fig. 1 and like that of Fig. 5.

Referring to Fig. 1, I have shown my invention embodied in a refractory wall 10 of a heating structure, such as a furnace, for example. The wall 10 comprises a plurality of preformed refractory shapes including a number of burner blocks 11 and filler blocks 12 of ceramic material. The burner blocks 11 are arranged in horizontal rows one above the other, and the blocks 11 in one row may be staggered with respect to the blocks 11 in the rows adjacent thereto, as shown in Fig. 1. While the blocks 11 in each row are spaced from one another by a single filler block 12, the blocks 11 may be adjacent to one another or disposed between several filler blocks 12.

The blocks 11 and 12 are held in abutting relation by a suitable high temperature cement and are of such size that a relatively thick refractory wall is provided. Each of the burner blocks 10 includes a cup-shaped radiator 14 of parabolic form, a distributor cap 15, and a passage 16 extending from the bottom of the radiator to the rear of the block.

Within the passages 16 are disposed burner tubes or sleeves 17 having the inner ends thereof terminating at regions closely adjacent to the inner ends of the passages 16. An intermediate part of each tube 17 is formed with an outwardly extending shoulder 18 which fits against a collar 19 positioned in a ring-shaped channel or groove 20. Within the outer end of each tube 17 is secured an end of a conduit 21, as by cement, for

2
example, through which a suitable combustible fuel mixture is supplied to the radiator 14.

The distributor caps 15 are threadedly secured at 22 to the inner ends of the tubes 17 and formed with a number of longitudinal slots or grooves 23 at the peripheries thereof for subdividing the combustible mixture to form a plurality of small gas streams. The gas streams are discharged from the distributor caps 15 at 24, as shown in Fig. 4, at which regions a plurality of relatively small burner flames are produced and maintained. The burner flames project outwardly from the distributor caps 15 at regions closely adjacent to and overlying the surfaces of the parabolic radiators 14 within which substantially complete combustion is accomplished. The radiators 14 are heated to a highly radiant condition and the refractory surfaces thereof reach temperatures of 2800° F. and higher when a combustible mixture is supplied to the burner blocks 11 comprising a mixture of air and ordinary city gas having a B. t. u. rating of about 530 B. t. u. per cubic foot.

The burner blocks 11 are formed of complementary sections 25 which, when assembled and joined together by high temperature cement, as indicated at 26, provide the burner blocks illustrated and just described. The faces of the sections 25 which come together may be formed with channels at each side of the central passage 16 so that, when the sections are secured together, passages will be formed to anchor bolts 27 in the blocks 11. The bolts 27 project beyond the rear of each burner block and are adapted to receive tightening nuts 28.

When each burner block 11 is initially formed and before the sections 25 thereof are united by cement, as just described, the collar 19 is placed in one section and accurately positioned a definite distance from the radiator 14 with the aid of high temperature cement 20a in the channel or groove 20 in which the collar 19 is embedded. Similarly, the heads of the anchor bolts 27 are accurately positioned in one section 25 of each burner block with the aid of high temperature cement, as indicated at 30, before the two sections are united together.

While the burner blocks 11 are formed from a pair of molded refractory sections 25, the filler blocks 12 are shown as one-piece molded refractory shapes. It is to be understood that the burner blocks 11 may also be formed as one-piece refractory shapes.

When the refractory wall 10 is employed as a wall of a heating structure having a heating space, it is desirable to utilize burner blocks 11

and filler blocks 12 formed of refractory material of such porosity that a poor thermal conductive path is provided through the wall, so that the heat loss from the heating space to the surroundings will be at a minimum. However, the strength of the refractory material is a function of its porosity. When refractory material of greater porosity is employed, a poorer thermal conductive path results; but such improvement in the thermal insulating properties of the material is accomplished by sacrifice in tensile strength.

The tensile strength of refractory shapes is an important consideration because of the thermal shock to which such shapes are subjected. Each time the heating space is heated from atmospheric temperature to an elevated temperature of about 2500° to 2800° F. and higher, for example, the refractory shapes are subjected to considerable thermal shock. Since the inner faces of the refractory shapes form a part of the inner refractory lining of the heating space and are heated to a highly radiant condition, the highest concentration of heat occurs at the regions of the shapes at and adjacent to the inner faces thereof. Further, when the shapes are formed of refractory material of poor thermal conductivity and the temperature gradient from the inner faces thereof to the rear surfaces is relatively high, stresses are induced in the refractory shapes.

When the heating space is repeatedly heated to elevated temperatures and then allowed to cool to the ambient temperature, refractory shapes formed of ceramic material of desired porosity are subjected to such thermal shock that cracks and flaws may develop which may eventually cause the shapes to split. Stated another way, the tensile strength of the refractory material having desirable thermal insulating properties is insufficient to withstand the stresses and strains induced therein by repeatedly heating the inner faces of shapes of such material to elevated temperatures and subsequently allowing these regions to cool to the temperature of the surroundings.

In the refractory wall 10 the inner faces of the burner blocks 11 are heated to a higher temperature than the inner faces of the filler blocks 12. This is so because of the combustion accomplished at the radiators 14 which heats the surfaces of the latter to a highly radiant condition. However, in many heating applications where a considerable number of burner blocks 11 are mounted in the walls of the heating structure, and especially where the burner wall is at close range to the work, the high temperature heated products of combustion sweep past the inner surfaces of the filler blocks 12 at high lineal velocities to heat such regions to a highly radiant condition approaching the temperatures maintained at the surfaces of the radiators 14.

Hence, the greatest concentration of heat occurs at the inner surfaces of the filler blocks 12 and at the surfaces of the cup-shaped radiators 14. When the blocks 11 and 12 are formed of refractory material of relatively high porosity to provide a poor thermal conductive path through the wall in which such blocks are mounted, cracks may develop at the regions adjacent to the inner faces of the blocks due to the stresses induced therein, as explained above. This is especially true when the burner blocks 11 are fired to exceptionally high temperatures by reason of the reduced cross sectional area of the blocks at the vicinity of the cup-shaped radiators 14.

When cracks and flaws do develop in the burner

blocks 11 at the vicinity of the cup-shaped radiators 14, parts of the blocks may break off and become dislodged and project beyond the inner surface of the wall 10. This reduces the efficiency of the burner blocks 11 and necessitates replacement of the blocks which requires shutting down the heating structure for making the necessary repairs.

In accordance with my invention, in order to increase the life of refractory shapes, the blocks 11 and 12 are formed of refractory material of poor thermal conductivity possessing the requisite thermal insulating properties, and tie rods 31 and 32 are embodied in each block to hold the latter together when heat is concentrated at their inner surfaces and stresses are induced in the blocks due to uneven heating of different regions thereof adjacent to and removed from the highly heated inner surfaces.

The tie rods 31 and 32 are preferably formed of refractory material of high tensile strength and provided with enlarged end portions, as shown in Figs. 5 and 6. In the wall 10 the burner blocks 11 in the top and middle rows and all of the filler blocks 12 are provided with spaced apart recesses 33 at the top and bottom surfaces thereof to receive the tie rods 31. The recesses 33 are deeper at the front and rear ends than at the intermediate portions, as shown in Figs. 2 and 3, to receive the enlarged ends 34 of the tie rods 31. The tie rods 31 are snugly secured in position, as by cement, for example, so that the blocks 11 and 12 and the tie rods 31 embodied therein are provided with smooth outer surfaces to facilitate mounting the blocks in the wall 10.

Tie rods 32 of the form shown in Fig. 6 are embodied in the burner blocks 11 in the bottom row of the wall 10. The tie rods 32 are of cylindrical shape and formed with enlarged rounded ends 35. The tie rods 32 are secured in position, as by cement, for example, in recesses formed by complementary semi-circular grooves or passages at the abutting surfaces of the sections 25.

The tie rods 31 and 32 effectively hold each of the blocks 11 and 12 together when the inner faces of the blocks are heated to a highly radiant condition and stresses are induced in the blocks due to the rear parts remaining relatively cool while the regions adjacent to and at the inner surfaces are heated to high temperatures.

Although the tensile strength of the refractory blocks 11 and 12 in and of themselves may be insufficient to withstand repeated thermal shock, the tie rods 31 and 32 of high tensile strength are capable of withstanding the thermal shock to which the blocks are subjected and tend to retard cracks developing in the blocks as well as to retard the growth of cracks after they once occur. Further, when the blocks 11 and 12 are subjected to repeated thermal shock over a long interval of time and the blocks may split, the tie rods 31 and 32 effectively hold each block together and prevent any part thereof being dislodged. Thus, in the event a part of a burner block 11 breaks off at the vicinity of the radiator 14, the tie rods effectively hold such part in place whereby the effectiveness of the burner block will not be impaired.

It will be seen that the shoulders 36 formed at the inner parts of the enlarged ends of the tie rods, which bear against the ends of the intermediate raised portions of the slots, are inclined or slanted and not square. However, such slanted or inclined shoulders 36 have been found satisfactory to grip the front and rear portions

of the blocks 11 and 12 whereby the latter may be maintained as unitary structures.

By way of illustration and without limitation I have successfully employed tie rods formed practically entirely or preponderantly of silicon carbide in burner blocks 11 like those shown and described and formed of mullite. Such burner blocks have been used in heating apparatus in which the work is relatively close to the burner wall and temperatures produced at the radiators 14 are as high as 3000° F. The heating application required cycling, that is, the burner wall was repeatedly heated to the desired high elevated temperature and then subsequently allowed to cool to the temperature of the surroundings. The tie rods of silicon carbide effectively held each mullite block together even though repeatedly subjected to thermal shock.

While the thermal conductivity of tie rods formed of silicon carbide is greater than that of the porous ceramic material of which the refractory shapes may be formed, such as mullite, for example, the cross sectional area of the tie rods collectively is relatively small compared to that of the refractory shapes; and the fact that the tie rods may be slightly less effective than the porous block material to keep the heat loss through the refractory wall at a minimum is more than compensated by the additional benefits gained whereby the inner faces of the shapes are anchored to the cooler rear portions thereof by material of high tensile strength.

Hence, in practicing the invention, the rear portions of the refractory shapes may be anchored by the bolts 27 to the outer metallic reinforcing parts of the heating structure and the inner faces of the blocks 11 and 12 are in turn anchored by the tie rods to the rear cooler portions of the blocks, whereby effective anchoring of the entire wall may be accomplished from the outer metallic parts directly to the inner faces of the blocks which form the inner refractory lining of a heating space.

Although several embodiments of the invention have been shown and described, it will be apparent to those skilled in the art that modifications may be made without departing from the spirit and scope of the invention, as pointed out in the following claims.

What is claimed is:

1. A refractory article comprising a body of refractory material of poor thermal conductivity having a first face thereof adapted to be subjected to a source of heat at an elevated temperature, said body having a recess which extends from a region adjacent to the first face to a region adjacent to an opposite face thereof, and a rigid tie rod in the recess which is formed of refractory material of greater tensile strength than the first-mentioned refractory material, the recess and tie rod therein being formed and arranged to hold said body together when said first face is subjected to the heat source and stresses are induced in the body due to uneven heating thereof at regions adjacent thereto and removed from said first face.

2. A preformed refractory article comprising a block of refractory material formed of two sections secured together and having a face thereof adapted to be subjected to a source of heat at an elevated temperature, said sections at their abutting surfaces having complementary recesses forming an opening which extends from a region adjacent to said face to a region adjacent to an opposite face of said body, and a rigid tie rod

5 positioned in the opening which is formed of refractory material of greater tensile strength than the first mentioned refractory material, the tie rod forming a component part of the article and having enlarged end portions and an intermediate connecting portion of reduced cross-sectional area.

3. A preformed refractory article comprising a body of refractory material of poor thermal conductivity having an opening therethrough from a first face to a second opposite face and a cavity at the first face adapted to be heated to a highly radiant condition by combustible fuel mixture supplied through the passage, said body having a recess which extends from a region adjacent to said first face to a region removed therefrom, and a rigid tie rod positioned in the recess which is formed of refractory material of higher tensile strength than the first-mentioned refractory material, the tie rod having enlarged end portions and an intermediate connecting portion of reduced cross sectional area.

4. A preformed refractory article comprising a body of porous ceramic material of poor thermal conductivity having a passage therethrough from a first face to a second opposite face and a cavity at the first face adapted to be heated to a highly radiant condition by combustible fuel mixture supplied through the passage, and a rigid tie rod embodied in the body which rod extends from a region adjacent to said first face toward the second face, said tie rod being formed of refractory material including silicon carbide having greater tensile strength than the ceramic material and having enlarged end portions and an intermediate connecting portion of reduced cross sectional area.

5. A burner block comprising a body of refractory material of low thermal conductivity having opposed faces and opposed sides, said body being formed with a cavity in one face and a passage extending from said cavity to the opposite face thereof, said body also being formed with a recess on each of said opposed sides, extending from face to face, and a heat resisting refractory tie rod received in each of said recesses, said tie rods acting to reinforce the faces of said block.

6. A burner block according to claim 5 in which said recesses have enlarged ends adjacent said faces, and enlarged ends on said tie rods received in the enlarged ends of said recesses.

7. A burner block comprising a body of refractory material formed with opposed faces and a burner cavity in one face, a recess formed in said body and extending between said faces and a tie rod of heat resisting refractory extending between said faces and completely received by said recess and forming an integral portion of said body, said tie rod serving to reinforce the faces of said body.

8. A refractory article comprising a block of refractory material having low heat conductivity, said block being provided with a pair of opposed faces one of which is to be subjected to a source of heat at an elevated temperature, and sides extending between said faces, one of said sides being provided with a recess extending from face to face of said article, and a rigid refractory insert received in said recess, said insert being formed of refractory material having a higher tensile strength than said first refractory material.

9. The combination of claim 8 in which said recess is deeper at said faces than at the region

between said faces and said insert is provided with enlarged portions received by said recesses.

10. The combination of claim 8 in which said article is mullite and said insert is silicon carbide.

11. A burner block of refractory material having low heat conductivity, said block having opposed faces and sides joining said faces, one face being adapted to be subjected to high temperature whereby internal stresses are set up in said block tending to crack the same, said sides being provided with recesses extending from one face to the other, and an insert of refractory material having high tensile strength at said temperature received in each of said recesses and serving to reinforce said block to prevent cracking of the same.
